UNITED STATES PATENT OFFICE.

OTTO STAVENHAGEN, OF CHARLOTTENBURG, NEAR BERLIN, GERMANY.

LETTER FILE OR REGISTER.

1,414,758.

Specification of Letters Patent. Patented May 2, 1922.

Application filed May 7, 1917. Serial No. 166,913.

(GRANTED UNDER THE PROVISIONS OF THE ACT OF MARCH 3, 1921, 41 STAT. L., 1812.)

To all whom it may concern:

Be it known that I, OTTO STAVENHAGEN, chartered accountant, a subject of the King of Prussia, German Empire, and residing at 5 Charlottenburg, near Berlin, Germany, have invented certain new and useful Improvements in Letter Files or Registers, of which the following is a specification.

The present invention consists of an improvement of the letter file or register as described in my prior application for patent filed March 24, 1917, Serial Number 157,272. The invention of my said prior application for patent consists in using the space now lost in the present letter files by their triangular form by adjusting a second letter file to the usual letter file. This second letter file is joined to the first according to my prior invention in opposite direction and situation.

According to the present invention there will be also combined two known letter files to a rectangular form like a book but in such a manner that the second letter file is fastened with its middle part to the edge of the one cover or side part of the first letter file so that the filing bows of both letter files are situated in the same direction and parallel to each other if the whole letter file is opened, and so that the letters or papers of both letter files lie open in the same direction.

In closing the new letter file the second letter file will be turned through an angle of 180° and brought above the first letter file and then the whole letter file will be closed by the free side part or cover of the first letter file. By this arrangement after opening the new letter file both piles of papers or letters lie in the same position near each other and after closing the new letter file an unintentional unclasp of the letter file is prevented.

It is preferable in order that the second letter file may be turned above the first letter file to lengthen somewhat the wellknown bow or arm which presses upon the letters or papers and used to put back the papers or letters by turning it around the file arches, so that one can grasp this bow or arm in order to prevent the turning over of the leaves or letters of the second letter file in opening the new letter file.

The invention is illustrated by way of example in the drawing:

55

Fig. 1 shows the new letter file closed,

Fig. 2 is an edge view on a smaller scale of the letter file when opened and

Fig. 3 is a plan view of the file partly closed.

60

According to the present invention an ordinary letter file consisting of the cover *a*, middle or back part *b* and cover *c* with the usual file arch *d* has a second letter file combined with it in such manner that the middle or back part *e* of this second letter file is hinged to the edge of the lower cover *c* of the first letter file. The second letter file has only one cover *f* which constitutes a carrier for the file arch *g* of this letter file. To close the whole letter file this cover *f* of the second letter file must be turned over, so that then both file arches lie opposite to each other and in opposite directions. The papers in both letter files will then lie above each other, 75 the well known arms or bows *h* and *i* pressing upon the papers.

The cover *a* of the first letter file extends to the edge of the back part *e* of the second letter file. If closed the new letter file has 80 a rectangular cross section. If opened both file arches lie parallel and in the same direction near each other so that one can see the papers of both letter files in the proper position to be read. In order to facilitate the 85 opening of the letter file and in order to prevent the turning over of the papers of the second letter file it is preferable to lengthen the arm or bow *i* of this letter file so that it extends beyond the papers and the cover of 90 this letter file as shown in the drawings. In order to obtain this effect this arm or bow *i* has an extension *i'* lying between the two parts of the filing arch *d* of the first letter file if the new letter file is closed as shown 95 in Fig. 3.

The present invention allows the adjustment of a lock, one part of a lock being adjusted on the outer side of the second letter file and the other part being fastened to the 100 free cover *a* of the first letter file, so that the whole letter file after being closed can be locked.

I claim:

1. The combination with a letter file comprising a portfolio having a filing arch

105

- therein, of a letter file comprising a filing arch, and a carrier for the latter connected to the portfolio and adapted to be contained within the latter.
5. 2. A letter file or the like comprising a portfolio, a filing arch mounted on one of the sides thereof, a second filing arch, and a carrier for the latter connected to one of the sides of the portfolio and adapted to be 10 folded within the latter.
3. A portfolio having a filing arch mounted on its lower side, a back portion hinged to the outer edge of said lower side, a carrier hinged to said back portion and adapted 15 to be contained between the sides of the portfolio, and a filing arch on said carrier adapted to lie between the carrier and one side of the portfolio.
4. A letter file comprising a cover, a filing 20 device mounted thereon near one end thereof, a carrier in hinged connection with the other end of said cover and adapted to be folded over the latter, a filing device on the carrier adjacent said hinged connection and 25 adapted to be contained between the cover and carrier and a cover for the carrier connected to the first named cover.
5. A letter file comprising a cover, a filing device mounted thereon near one end thereof, a carrier in hinged connection with the 30 other end of said cover and adapted to be folded over the latter, a filing device on the carrier adjacent said hinged connection and adapted to be contained between the cover and carrier, and an arm connected with the 35 carrier and extending in the direction of the free end of the latter.
6. A letter file comprising a cover, a filing device mounted thereon near one end thereof, a carrier in hinged connection with the 40 other end of said cover and adapted to be folded over the latter, a filing device on the carrier adjacent said hinged connection and adapted to be contained between the cover and carrier, and a hinged arm connected 45 with the carrier adjacent the filing device thereon and extending beyond the free end of the carrier, for the purpose specified.

In testimony whereof I have affixed my signature in the presence of two witnesses. 50

OTTO STAVENHAGEN.
